US0D1086997S

(12) **United States Design Patent** (10) **Patent No.:** **US D1,086,997 S**
(45) **Date of Patent:** ** Aug. 5, 2025

(54) **CHARGER FOR ELECTRIC VEHICLE**

(71) Applicant: **LG ELECTRONICS INC.**, Seoul (KR)

(72) Inventors: **Bumsang Lee**, Seoul (KR); **Seungdon Lee**, Seoul (KR); **Sangwon Yoon**, Seoul (KR)

(73) Assignee: **LG ELECTRONICS INC.**, Seoul (KR)

(**) Term: **15 Years**

(21) Appl. No.: **29/906,634**

(22) Filed: **Nov. 7, 2023**

(30) **Foreign Application Priority Data**

May 10, 2023 (KR) 30-2023-0017787

(57) **CLAIM**

The ornamental design for a charger for electric vehicle as shown and described.

DESCRIPTION

FIG. 1 is a bottom perspective view of a charger for electric vehicle showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view of the charger for electric vehicle shown in an environment of use; and,

FIG. 9 is a bottom perspective view of the charger for electric vehicle shown in an environment of use and in an alternate configuration.

The broken lines depict portions of the charger for electric vehicle that form no part of the claimed design. The charging

(Continued)

cable shown in broken lines in FIGS. 8 and 9 show environmental structure only and form no part of the claimed design.

1 Claim, 9 Drawing Sheets
